UNITED STATES PATENT OFFICE

EDWARD CHESHIRE, OF PITTSBURGH, PENNSYLVANIA, ASSIGNOR TO MILLER SAW TRIMMER COMPANY OF MICHIGAN, OF PITTSBURGH, PENNSYLVANIA, A CORPORATION OF MICHIGAN.

TABLE-ELEVATING MECHANISM.

1,145,404.

Specification of Letters Patent. Patented July 6, 1915.

Application filed September 18, 1913, Serial No. 790,524. Renewed May 29, 1915. Serial No. 31,313.

To all whom it may concern:

Be it known that I, EDWARD CHESHIRE, a citizen of the United States, residing at Pittsburgh, in the county of Allegheny and State of Pennsylvania, have invented new and useful Improvements in Table-Elevating Mechanism, of which the following is a full, clear, concise, and exact description, reference being had to the accompanying drawing, forming a part of this specification.

My invention relates to table elevating mechanisms for use in connection with machinery for handling sheets of paper, card-board blanks, and like articles.

The principal object of my invention is the provision of table elevating mechanism which will be simple in construction and which will perform its functions in an efficient and satisfactory manner.

It is a further object of my invention to provide the table elevating mechanism with a simple and convenient adjustable device by means of which the raising force applied to the table may be readily adjusted to accord with the size and nature of the material upon the table. And it is a still further object of my invention to provide an adjustable device of the above character of such a nature that the upward pressure imparted to the table will be substantially uniform regardless of the size or nature of the paper being used.

A mechanism embodying my invention is described, by way of example, in the following specification and shown in the accompanying drawings. This mechanism is described and shown as employed in connection with a paper feeding and handling machine of the kind disclosed in my co-pending application, Serial No. 790,525, filed Sep. 18, 1913, but it may be employed in other connections. I wish it understood, moreover, that the invention may be embodied in other forms than that which is described, and that changes may be made in the constructional features of the embodiment which is described, without exceeding the scope of the invention, as defined in the appended claims.

In the drawings: Figure 1 is a rear elevation of the mechanism; Fig. 2 is a vertical section, on a somewhat larger scale, through the mechanism, the section being

taken as on the line 2—2 of Fig. 1, looking in the direction of the arrows; Fig. 3 is a detail section, on an enlarged scale, taken on the line 3—3 of Fig. 2, looking in the direction of the arrows; Fig. 4 is a detail section, on an enlarged scale, taken on the line 4—4 of Fig. 1, looking in the direction of the arrows; and Fig. 5 is a schematic view illustrating the manner of determining the relative sizes and positions of the parts.

As has been said, the embodiment of my invention shown in the drawings is applied to a paper feeding and handling device of the kind described in my co-pending application, above referred to. Such a device includes a feed box 10 having side flanges 65 by means of which it is adapted to be secured to the frame 11 of a platen press. Extending downward from the feed box 10 is a hollow guide 12 in which is slidably mounted a vertical pillar 13 extending 70 downwardly from a floating stock table 14. The paper which is to be fed to the press is placed on the stock table 14 and is normally pressed upward against a plurality of pneumatic feet 15 which are secured to 75 a separator bar 16. The separator bar 16 is carried by a feeder frame 17 which is mounted on the feed box 10. The pneumatic feet 15 form stops for limiting the upward movement of the pile of stock carried by the table 14 and are intermittently 80 lifted to carry the top sheet of the pile 85 into position to be removed by a feeding device (not shown). The table 14 is clamped against upward movement during such lifting of the pneumatic feet 15, by mechanism 90 which will be hereinafter described.

A guide 18 is secured to the feed box 10 and is formed with a guide slot 19 in which is slidably mounted a block 20 carrying at its 95 outer end a fulcrum pin 21 (Figs. 1 and 4). The block 20 is hitched, by means of a rod 22 to a pivoted lever 23; so that, by shifting the lever 23 in one direction or the other, the block 20 may be moved in a corresponding 100 direction in the slot 19 of the guide 18. The fulcrum pin 21 enters a slot 24 in a lifting lever 25 which is connected, by means of a pin 26, to a pivoted link 27 extending downwardly from the floating stock table 14. 105 Connected to the lifting lever 25 by a pin 28, between the pin 26 and the end of the slot 24, is a shank 29, the lower face of

which is engaged, and pressed upward, by a compression spring 30. It will be seen that the spring 30, acting through the shank 29, lever 25 and link 27 will tend to force the table 14 upward, and to press the upper face of the pile of paper against the pneumatic feet 15. It will also be seen that by shifting the block 20 to the right or to the left in the slot 19, the effect of the spring 30 to raise the table 14 will be correspondingly increased or lessened. Without means for preventing such movement being provided, the lever 25 might move endwise with respect to the pivot 21. A spacing link 31 is, therefore, connected between the pin 26 and a pin carried by a lug 32 secured to the guide 18, and serves to define the relative positions of the parts described above. By reason of the provision of this spacing link, the block 20 and fulcrum 21 will be caused to slide slightly in the slots 19 and 24, during the upward movement of the table, but this sliding movement is so small as to have no appreciable effect on the operation of the device.

The spring 30 is only allowed to exert its pressure upon the table 14 at certain intervals, the table being normally locked against movement by a clamping device now to be described. The clamping device consists of a clutch 34 which operates upon the lower end of the pillar 13. The clutch 34 consists of a block 35 slidably mounted in a hollow boss, situated at the lower end of the guide 12, and having a slot 36 therein through which the pillar 13 passes. A coiled spring 37 abuts against the end of the block 35 and normally forces the end surface of the slot 36 into engagement with the pillar 13 whereby the stem is held against movement. The clutch is intermittently released by means of a cam projection 38 which is secured to the driving shaft 39 of the press. The cam projection 38, at each revolution of the shaft 39, engages a roller 40 carried by the block 35 and thus forces the block inward against the action of the spring 37, whereby the pillar 13 is released and the floating stock table 14 al-

lowed to be moved upward by the action of the spring 30.

As has been stated above, the upward movement of the floating stock table 14 is limited by the pneumatic feet 15 carried by the separator bar 16, against which feet the upper face of the pile of paper presses. The pneumatic feet 15 are held stationary during the time that the clutch 34 is released; but they are subsequently raised to lift the top sheet of the pile into position for feeding. After a sheet has been thus lifted and the separator bar 16 and pneumatic feet 15 have again returned to their lower position, the pile will not, of course, press so firmly against the pneumatic feet as before. Just

at this time the cam projection 38 forces the block 35 inward and releases the pillar 13, whereupon the table is raised by an amount substantially equal to the thickness of the sheet removed. The table is thus raised to the extent of the thickness of one sheet at each revolution of the main driving shaft 39.

In order that the floating stock table 14 may be moved downward to receive a new pile of stock and in order to enable the operator to adjust the height of the floating table manually when desired, a clutch actuating hand lever 41 is pivoted to the casing of the clutch 34 in such position as to engage, by means of its bent over end 42 (Fig. 3), a shoulder 43 formed upon the clutch block 35. By moving the clutch actuating lever 41 to the left, its end 42 is forced against the shoulder 43 and the clutch block 35 is thereby forced inward against the action of the spring 37, the pillar 13 being thus released. When the pillar 13 has been released the floating stock table may be manually pressed down against the action of the spring 30 to any extent desired.

In order that the floating stock table 14 may be locked in its lowermost position, if desired, during the operation of the press, the outer end of the hand lever 41 is provided with a hook 44 which may be made to engage over the end of the lever 25, whereby the floating table is securely retained in the lowermost position.

The floating table 14 is formed with transverse slots through which project vertical side guides 45 between which the pile of stock is placed upon the floating table, the front of the pile resting against end stops 46 which are provided at the front of the feed box 10. The side stops 45 are laterally adjustable for different widths of paper, and different positions of the paper on the stock table, and are similar to one another, so that a description of one of them will suffice. Each of the stops 45 is slidably mounted upon a transverse guide bar 47 carried by the feed box 10 beneath the floating stock table, and is provided with a screw hole into which is threaded the end of a rod 48 which extends to the rear of the feed box. The end of the rod 48 is arranged to bear against the guide bar 47 and thus lock the side stop 45 against movement. However, when it is desired to adjust the stop, this may be done by turning the rod 48 so as to release its end from engagement with the guide 47, when the stop may be manually moved to the right or left by means of the rod 48. An adjustable end stop 50 is provided on the stock table 14 for engaging the rear face of the pile of stock.

Reference has been made above to the fact that the pivot fulcrum 21 is shiftable in the slots 19 and 24 of the guide 18 and raising lever 25, respectively, in order to enable the

pressure exerted by the spring 30 upon the table 14 to be varied, this being for the purpose of adapting the pressure applied to the table to the weight, per unit of thickness of the pile, of paper upon the table. It will be understood that variations of the weight of the paper, due to variations of the thickness of the pile, are automatically compensated for by the variations of the compression of the spring due to the greater or less lowering of the table necessary to enable a thick pile or a thin pile, respectively, to be placed thereupon beneath the pneumatic feet 15. The area of the paper, and what 5 may be termed the specific weight of the paper, may, however, vary within wide limits, and this variation is compensated for by shifting the fulcrum 21, as described above.

10 In practice, a pile of paper is placed upon the table 14, the clutch 34 having been previously released to allow the table to be depressed. The handle 23 is then moved to shift the block 20, and consequently the fulcrum 21, in one direction or the other, until the spring is causing a certain predetermined upward pressure. As the paper is removed from the pile sheet by sheet, and the table 14 is raised step by step, the spring 15 will gradually expand, thereby exerting a gradually diminishing pressure upon the table. This diminution of the pressure applied to the spring 30 will be proportional to the reduction of weight of the paper on 20 the table so that, when the paper is all removed, the table itself will engage against the pneumatic feet with the same pressure as the pile did when first placed upon the table. This condition would be present as 25 a matter of course were it not for the weight of the stock table and associated parts, and the constant upward pressure which it is desired that the stock exert upon the pneumatic feet. In order that the condition may 30 be present in practice, therefore, it is necessary to compensate for the constant weight of the table and associated parts, and for the desired constant upward pressure of the pile. This compensation is effected by providing an initial compression of the spring 30, and disposing the slot 19 at such an inclination that this initial compression will 35 remain constant regardless of the position of the block 20 in the slot 19.

40 Let it be considered, for example, that the weight of the table and associated parts is 7 lbs., that the desired constant upward pressure of the pile is 2 lbs., that the leverage of the lever 25 is $\frac{1}{7}$ for the lightest paper, and that such leverage is $\frac{4}{7}$ for the heaviest paper. Considering now the position of the fulcrum 21 shown in full lines in Fig. 5 (in which the leverage is $\frac{7}{4}$), it will be seen that in order to give the required constant upward pressure of 9 lbs. 45 to the stock table, there must be such an initial compression of the spring 30 as will give a pressure of 63 lbs. at the pin 28. If the slot 19 lay in a line with the slot 24, the shifting of the fulcrum 21 would work 50 no change in the initial compression of the spring; so that, with the fulcrum 21 shifted to the opposite end of the slot 19, there would still be an upward pressure of 63 lbs. at the pin 28. The leverage having been 55 changed to $\frac{4}{7}$, there would be an upward pressure of 21 lbs. at the stock table, instead of the 9 lbs. which was desired. To avoid this, and maintain the upward pressure of the stock table constant at all times 60 the slot 19 is inclined in such a manner as to maintain the initial compression of the spring in proper proportionate relation with the leverage at all positions of the fulcrum 21. This will be clear from an inspection 65 of Fig. 5 which shows, in full lines, the position of the parts for the lightest paper, and, in dotted lines, the position of the parts for the heaviest paper. It will be noted that the initial compression of the spring is much 70 greater in the full line position than it is in the dotted position.

75 By the above described mechanism, the pile of stock is raised steadily and uniformly until the last sheet has been removed and the table itself engages against the pneumatic feet 15; and the pressure against the feet 15 remains constant during such raising. The mechanism is of a simple nature, is easy to manipulate, and is not liable 80 to get out of order. Stock may be placed on the table or removed, and the adjustments made for different sizes and natures of stock, with great ease and speed.

85 Having thus described my invention, what I claim as new and desire to secure by Letters Patent, is:

90 1. A table elevating device comprising a floating table for receiving articles piled one on the other and from which such articles are adapted to be removed in successive quantities, means for exerting an upward pressure on said table to maintain the top of the pile at a required level, said pressure exerting means being arranged to decrease 95 in effect as the weight of the pile diminishes owing to the removal of the articles, and means for adjusting said pressure exerting means in accordance with the initial weight 100 of said pile of articles, said last-named means being self-adjusting to compensate 105 for the constant weight of the table.

110 2. In a table elevating device the combination with a movable table for receiving articles piled one on the other and from which such articles are adapted to be removed in successive quantities, of a lever co-operatively related with said table and adapted for raising the latter, a spring for 115 actuating said lever, said spring being ar- 120

125 65 60 55 50 45 40 35 30 25 20 15 10 5 0

ranged so as to exercise an extra pressure to compensate for the weight of the table itself, a settable fulcrum for said lever whereby the effective operating length of 5 said lever may be varied in accordance with the weight of the particular articles carried by the table, and means whereby the extra pressure exercised by said spring for compensating for the weight of the table may 10 be adjusted in proportion to the change of leverages effected by the setting of said fulcrum.

3. In a table elevating device, the combination with a movable table, of a spring- 15 actuated slotted lever adapted for elevating said table, a slotted guide, the slot in said guide being inclined with respect to the slot in said lever, and a fulcrum for said lever, said fulcrum being shiftably mounted in said slotted guide and slotted lever, 20 for the purposes set forth.

4. In a table elevating device, the combination with a movable table, of a spring- 25 actuated lever coöperatively related to the table and adapted for raising the latter, and a settable fulcrum for said lever, whereby the effective operating length of said lever may be varied at will.

5. In a table elevating device, the combination with a vertically movable table of 30 a spring-actuated pivoted lever coöperatively related to the table and adapted to raise the latter, and a member having a slot therein for adjustably receiving the pivot 35 of said lever, whereby the effective operating length of said lever may be varied at will, said slot being inclined so as to compensate for the constant weight of said table.

6. In a table elevating device, the combination with a movable table, of a spring- 40 actuated lever coöperatively related to the table and adapted for raising the latter, a settable fulcrum for said lever, whereby the effective operating length of said lever may 45 be varied at will, means for checking the elevation of the table, and periodically acting means for releasing the table to permit the spring-actuated lever to elevate said table.

50 7. In a table elevating device, the combination with a movable table, of a spring- actuated slotted lever adapted for elevating said table, a slotted guide, a fulcrum for said lever which is shiftable in said slotted 55 guide and slotted lever, and a hand-operated device adapted for shifting the lever fulcrum to different positions in the slotted guide, whereby the effective leverage co-

operating with the table may be varied at will.

8. In a table elevating device, the combination with a movable table, of a lever operatively connected thereto, a fulcrum for said lever, spring means coöperating with the lever between its fulcrum and point 60 of application to the table adapted for effecting the movement of the table, and means for shifting said fulcrum, thereby to vary the effective length of the lever, with which the spring means coöperates.

9. In a table elevating device, the combination with a movable table, of a spring- 65 actuated lever operatively connected thereto, a shiftable fulcrum for said lever, and a spacing link extending along side of the lever aforesaid which is pivoted and is also operatively connected to the table.

10. In a table elevating device, the combination with a movable table, of a spring- 70 actuated lever, a link pivoted to the lever and to the table, a shiftable fulcrum for said lever, and a spacing link extending alongside of the lever aforesaid which is pivoted and is also pivoted to the link aforesaid where the spring-actuated lever is pivoted thereto.

11. In a table elevating device, the combination with a movable table, of a spring- 75 actuated lever coöperatively connected thereto, a settable fulcrum for said lever, whereby the action of the lever on the table may be regulated, a releasable clamp for locking the table, automatically acting means for periodically releasing said clamp, and hand-operated means for releasing the 80 clamp at will.

12. In a table elevating device, the combination with a movable table adapted to hold articles piled one on another and from which such articles are adapted to be removed in successive quantities, of a lever for elevating said table to keep the top thereof at a required level as successive articles are removed, said lever having an adjustable fulcrum, means for actuating said lever, and 90 means for readily determining the proper position of said fulcrum in accordance with the initial weight of said pile of articles.

In witness whereof, I have hereunto subscribed my name in the presence of two witnesses.

EDWARD CHESHIRE.
